UNITED STATES PATENT OFFICE

FRANK ARRIGO, JR., AND FRANCESCO SUNSERI, OF LOS ANGELES, CALIFORNIA

POWDER INSUFFLATOR

Application filed August 31, 1927. Serial No. 216,606.

Our invention relates to powder insufflators, and more particularly to a device for conveniently placing a discharge of powder or other medicaments, other than fluid, into 5 a cavity for the treatment thereof.

In most of the devices with which we are familiar the various parts thereof are all connected together and must be handled during the insertion of the nozzle into the cavity to 10 be treated, with considerable inconvenience and awkwardness. We have conceived the idea of a nozzle which can be conveniently handled and put into place without any other part attached thereto, the outer end of 15 said nozzle being open and adapted to have inserted thereinto telescopically the load carrying tube, said load carrying tube having means connected therewith for causing a blast of air to force the powder or medicament therefrom and through the inserted 20 nozzle to the place to be treated, thus making it possible to first place the nozzle into the cavity to be treated, with such expanders or guards as may be provided therewith, and 25 then to insert the end of the load carrying tube into the open end of the nozzle and make the discharge. This avoids the trouble and inconvenience of having to handle the bulb or other air blast means and the powder or 30 other medicaments during the placement of the nozzle, and greatly simplifies the use of the instrument.

In order to fully explain our invention, we have shown one practical embodiment thereof on the accompanying sheet of drawings, 35 which we will now describe.

Figure 1 is a side elevation of a nozzle with expanders in their contracted positions; 40 Figure 2 is a side elevation thereof, with certain of the expanders omitted to make the view clearer, and showing the tubular nozzle moved inwardly to expand the expanders as they are expanded after being first inserted 45 into the cavity;

Figure 3 is a side elevation of the powder carrying tube and air blast bulb; and

Figure 4 is a side elevation of the nozzle and expanders with the powder carrying tube 50 inserted ready for discharge of the powder,

part of the nozzle being shown in section to show the inner end of the powder tube.

Referring now more in detail to the drawings, the invention as here illustrated, comprises a tubular nozzle 5, having the discharge openings 6, in its end, with a disc 7 thereon, and with a sleeve 8, thereon, and at its outer end provided with a stop or nut 9, the outer end of said tubular nozzle being open and free to receive therein the tube carrying the powder or other medicament, as hereinafter referred to.

Slidably mounted on said nozzle is a collar 10, provided with a series of spring wire expanders 11, extended forwardly and adapted 65 to normally converge at their forward ends, in the manner shown in Fig. 1, but to be expanded by said disc 7, when said tubular nozzle is moved forwardly through said collar 10, and into said expanders, as indicated in 70 Fig. 2. The sleeve 8, acts as a limit stop to prevent said tubular nozzle from being withdrawn sufficiently to place the disc 7, in the larger portions 11' of said expanders. The nut 9, also serves as a limit stop to prevent the 75 nozzle from being pushed through the collar 10 too far.

Referring to Fig. 3, a powder carrying tube 12, of glass, is provided with a rubber bulb 13, to cause an air blast through said 80 tube. Said tube is provided at its end with graduations, as 14, to indicate the amount of powder or other matter therein. This tube is loaded by inserting the end thereof into a body of powder the desired depth, the powder 85 remaining in the end of the tube. When the nozzle and expanders have been inserted into the cavity to be treated and adjusted as desired, which can be conveniently done because there is no tube or other apparatus connected therewith, the powder tube and bulb can be readily inserted into the open outer end of 90 said nozzle, and when the bulb 13 is compressed, said powder is blown through the nozzle openings 6, in a cloud so as to reach 95 all parts to be treated, the expanders operating to hold all parts open or expanded to make sure of exposure to the powder treatment.

We do not limit our invention to the details 100

as here shown for purposes of explanation, realizing that many changes can be made without departing from the spirit thereof, except as we are limited by the hereto appended claims.

5 We claim:

1. A powder insufflator including in combination a tubular nozzle member having expanders thereon and adapted to be inserted 10 into the cavity to receive the powder, the outer end of said tubular nozzle member being open to receive another tubular member, said tubular nozzle member having on its inner end means for expanding said expanders as 15 said tubular nozzle member is moved telescopically therein, and a powder holding tube adapted to have its end thrust into powder to pick up the desired amount thereof and to be inserted telescopically into the outer open 20 end of said tubular member, and means connected with said tube for causing a blast of air through said tube and said tubular member to blow said powder therefrom, substantially as shown and described.
- 25 2. A powder insufflator including in combination, a tubular nozzle, wire expanders around said nozzle and adapted to be expanded and contracted as said tubular nozzle is moved longitudinally therethrough, said nozzle having a disc like member on its end to move said expanders and a limit stop to limit its movement in said expanders, the outer end of said tubular nozzle being open and disconnected to receive telescopically a powder 30 containing tube, a powder holding tube adapted to have its end thrust into a body of powder to pick up the desired amount thereof, said tube being marked near its end to indicate the amount of powder therein, and 35 a bulb on the opposite end of said powder holding tube to blow said powder therefrom, said tube being adapted to have its powder containing end inserted telescopically into the open end of said tubular nozzle after the 40 same has been put into place into the cavity to receive the powder treatment.

Signed at Los Angeles, Los Angeles County, California, this 27th day of August, 1927.
